TRAY FOR ACCOMMODATING DATA PROCESSING CARDS

David M. Wright, 177 Spring St., Shrewsbury, Mass.
01545, and Carl J. Dean, R.F.D. 1, Southbridge, Mass.
01550

Filed Oct. 20, 1971, Ser. No. 191,155

Term of patent 14 years

Int. Cl. D14—02

U.S. Cl. D26—5 C

FIG. 1

FIG. 2

FIG. 3

FIG. 4

FIG. 1 is a perspective view of a tray for data processing cards embodying our new design.

FIG. 2 is a top plan view of the design.

FIG. 3 is a side elevational view of the design, and
FIG. 4 is a rear elevational view of the design.

The broken line representation of cards and their fol-
lowers in FIGS. 1 through 3 is for purposes of illustra-
tion only.

We claim:

The ornamental design for a tray for accommodating
data processing cards, as shown and described.
